Primary Examiner — David Muller*Assistant Examiner* — Nathan Johnston(74) *Attorney, Agent, or Firm* — Price Heneveld LLP(57) **CLAIM**

ornamental design for a portable urinal device, as shown and described.

DESCRIPTION

FIG. 1 is a perspective view of a portable urinal device showing my new design;

FIG. 2 is a left-side elevation view thereof, the right-side elevation view being a mirror image thereof;

FIG. 3 is a front elevation view thereof;

FIG. 4 is a rear elevation view thereof;

FIG. 5 is a top plan view thereof; and,

FIG. 6 is a bottom plan view thereof.

The portions shown in broken lines do not form part of the claimed design.
